UNITED STATES PATENT OFFICE

EMANUEL SOBEK, OF VIENNA, AUSTRIA

DISCHARGE FUNNEL FOR KILNS

Application filed August 28, 1928, Serial No. 202,508, and in Czechoslovakia January 19, 1928.

This invention relates to a discharge funnel of the type for which Letters Patent No. 1,668,825 have been granted me and which is employed in connection with kilns for burning lime, sintering dolomite and furnaces for roasting iron ores and the like, and has for its object to insure the best possible utilization of the fuel by providing free and unhampered admission of the air 10 of combustion or its gases to the fire inside the kiln. Kilns of the kind mentioned are usually filled with material to such an extent that the introduction of the air of combustion or of the gas is made difficult owing to obstacles which the present invention 15 seeks to remove.

In applicant's device covered by United States Patent 1,668,825 guide plates radiating from the center of the funnel and held 20 together in the center by a plate are shown, the plate being covered by a cone to prevent the material to be treated from accumulating on the plate and forming an obstacle for the material following it.

According to the present invention this 25 cone is used as a nozzle for supplying the seat of the fire with the air of combustion. Moreover, the discharge funnel is also provided with a ring nozzle, the nozzles being 30 formed so that a projecting and rounded rim is arranged on top of their upwardly inclined slots whereby the material moving downwardly through the furnace is kept away from the openings and the air or gas 35 is permitted to move freely upwards in the direction of the nozzle openings.

One form of the invention is illustrated 40 in the accompanying drawing, in which Fig. 1 is a longitudinal section of the lower part of the furnace, Fig. 2, a top view of Fig. 1, partly in section, Fig. 3 a longitudinal section of the cone nozzle, Fig. 4 a top view of the same partly in section on the line *c-d*, Fig. 3. Fig. 5 a longitudinal nozzle 45 and Fig. 6 a longitudinal section of the ring nozzle. Figs. 3-6 are drawn on a larger scale than Figs. 1-2.

Referring to the drawing, in the center 50 above the point of connection of the guide plates a nozzle 1 is provided having a conical

shape with a convex base 2 and a rounded rim 3 (Fig. 3). The nozzle 1, whose openings 5 incline upwardly, distributes the air of combustion supplied by the piping 11 and its cross section is adapted to that of the kiln, the cross section of the nozzle being, for instance, circular in case of a circular kiln and square or elliptical if the furnace shows the same cross section. Furthermore the nozzle 1 may also pass horizontally 55 through the entire furnace, but its longitudinal section must always show the shape described (Fig. 5).

The convex base 2 of the cone nozzle 1 (Fig. 3) forms an internally narrowing neck 4 carrying the nozzle slots 5 and the rounded rim 3 of the base 2 projects over this neck 4 to protect the slots 5 and prevent them from being clogged by the material dropping down to the funnel entrance. 60

On the circumference of the patented discharge funnel and somewhat above it in the brickwork 6 of the inner shell of the furnace a ring nozzle 7 may be provided as shown in Figs. 1, 2 and 5. This ring nozzle is one-sided and represents one half of the conical or longitudinal nozzle, 8 being openings, 9 the projecting ring, 10 the convex end of the cone and 12 the air or gas supply. 70

In both cases the material moving down 80 the furnace is kept away from the nozzle slots 5 and 8 by means of the projecting rims 3 and 9 to prevent clogging. The nozzle openings 5 and 8 incline upwardly so that the air is guided to the seat of the fire 85 and will not alter its course, even if the lower doors of the kiln are opened for taking in fuel, the air entering through the doors being simply guided the same way.

Instead of air, gas may enter the combustion chamber in case of gas fired kilns. Or, under certain conditions gas may enter 90 through the nozzle 1 and the air through nozzle 7.

I claim:

1. In combination, a discharge funnel for kilns, a conical nozzle forming part of said discharge funnel and provided with upwardly inclined slots and a convex base forming part of the said nozzle and project- 100

ing over the said slots to keep material dropping through the kiln away from the said slots and to permit the free upward movement of gases along the said convex base without causing clogging of the said slots.

5 2. The combination according to claim 1 and an annular nozzle arranged adjacent the lower internal surface of the kiln.

10 In testimony whereof I have affixed my
signature.

EMANUEL SOBEK.
